[22] Filed: **Jul. 21, 1997**

The ornamental design for a combined protective grill and lens for portable lamp, as shown and described.

Related U.S. Application Data

DESCRIPTION

- [63] Continuation of Ser. No. 62,727, Nov. 22, 1996, abandoned.
[51] **LOC (6) Cl.** **26-99**
[52] **U.S. Cl.** **D26/119**
[58] **Field of Search** D26/60, 61, 63,
D26/65, 118, 119, 139; 362/269, 275, 287,
418, 419, 427, 376, 377, 378

FIG. 1 is a perspective view of a combined protective grill and lens for portable lamp showing my new design;
FIG. 2 is a front elevational view thereof;
FIG. 3 is a right side elevational view thereof;
FIG. 4 is a plan view thereof;
FIG. 5 is a left side elevational view thereof;
FIG. 6 is a rear elevational view thereof; and,
FIG. 7 is a bottom plan view thereof.

The broken line showing of a portable lamp in FIGS. 1 through 5 and 7 is for illustrative purposes only and forms no part of the claimed design.
